(57) **CLAIM**

The ornamental design for a smart watch case, as shown and described.

DESCRIPTION

FIG. 1 is a perspective view of a smart watch case; FIG. 2 is a frontal view of the smart watch case; FIG. 3 is a rear view of the smart watch case; FIG. 4 is a right side view of the smart watch case; FIG. 5 is a left side view of the smart watch case; FIG. 6 is a top view of the smart watch case; and, FIG. 7 is a bottom view of the smart watch case. The broken lines in the Figures show portions of the smart watch case that form no part of the claimed design. The oblique shade lines in the Figures shows the surface contrast, and not surface ornamentation.
